ADJUSTABLE FRAME

Marshall N. Anderson, Chicago, Ill., assignor to
 Sellstrom Manufacturing Company, Chicago,
 Ill., a corporation of Illinois

Application April 20, 1946, Serial No. 663,701

11 Claims. (Cl. 2—14)

1

The present invention relates to goggles and their frames, particularly of a type which are adjustable so as to fit them more accurately to the contour of the wearer's face.

Goggles, such as are worn by persons engaged in industries which present hazards to the human eye, have been known for a great many years. The types of eye protection provided usually include goggles which consist of individual eye-cups and a bridge piece, together with suitable elastic straps which hold the goggles to the eyes. Other types comprise complete helmets, which not only protect the eyes, but the entire face of the wearer.

Inasmuch as the type of goggles which employs individual eye-cups usually requires both hands to put on and remove, it is highly desirable to have light weight goggles which, while they protect the eyes from injury either by actinic light or by flying particles, will nevertheless have some of the characteristics of the two-piece goggles, particularly so far as lightness of weight is concerned.

Attempts have been made to produce shielding types of goggles which not only have the features of individual, and usually replaceable, lenses, but which also have side walls or temple pieces which protect the eye from particles which are approaching at an angle. Such goggles, however, will naturally be rigid and comparatively inflexible so that they have a tendency to fit inaccurately, and it is only occasionally that the contour of the portion in contact with the wearer's brow will have the proper shape to make a tight fit between the goggles and the brow.

One of the objects of the present invention is to provide one-piece goggles, preferably constructed from a single piece of plastic material, at least the frontal portion thereof being transparent.

A further object of the present invention is to provide goggles in which the bridge member and the temples or sideshields are integral with the frontal portion that serves the function of the separable lenses usually employed in ordinary goggles.

It is a further object of the present invention to provide goggles having an adjustable bridge member so that they will more accurately fit the brow of the wearer, being moreover provided with means to make the adjustment permanent once the goggles have been properly fitted to the brow of the wearer.

Another object of the invention is to provide goggles or goggles frames in which the bridge

2

member is sectionalized by transversely extending cuts or slots so that the various sections may be made to recede from or approach each other at one side, the frontal lens-carrying portion, which is usually vertically disposed, consisting of some sufficiently flexible material to partake of the movement of the sectionalized bridge member.

A further object of the invention is to provide goggles in which the means employed for holding the sectionalized bridge member in condition of proper adjustment also serves a secondary function of holding certain lens members in place.

Other objects of the invention will become evident from the further description hereinbelow when considered in connection with the accompanying drawings, in which

Figure 1 is a perspective view of one form of goggles within the purview of the present invention;

Fig. 2 is a front elevational view, on a somewhat enlarged scale, of the goggles shown in Figure 1;

Fig. 3 is a top plan view of the goggles shown in Fig. 2;

Fig. 4 is a bottom plan view of the goggles shown in Fig. 2;

Fig. 5 is a cross sectional view, on a still more enlarged scale, along the line 5—5 of Fig. 2;

Fig. 6 is a cross sectional view on the same scale as Fig. 5, along the line 6—6 of Fig. 3;

Fig. 7 is a perspective view of a modified form of goggles;

Fig. 8 is a front elevational view, on a somewhat enlarged scale, of the goggles shown in Fig. 7;

Fig. 9 is a top plan view of the goggles shown in Fig. 8;

Fig. 10 is a side elevational view of the goggles shown in Figs. 8 and 9;

Fig. 11 is a sectional view along the lines 11—11 of Fig. 10;

Fig. 12 is a perspective view of still another type of goggles; and

Fig. 13 is a fragmentary sectional view along the lines 13—13 of Fig. 12.

All of the various types of goggles shown in Figs. 1 through 13 have certain elements in common, as can best be seen from the perspective views constituting Figs. 1, 7 and 12, namely, in that the goggles consist of a frame having a substantially horizontally disposed bridge portion, one side of which is curved approximately to fit the brow of the wearer. The goggles also have side shielding or temple-contacting portions

which are substantially vertically disposed, and also a frontal portion which is vertically disposed, but substantially at right angles to the plane of the temple portions, and which frontal portion serves to carry either the lens-mounts of the goggles shown in Figs. 1 and 7, or the single lens of the goggles shown in Fig. 12. In all of these cases, however, the bridge member is divided into at least two sections by means of a transverse slit or slot which extends about to the frontal portion of the frame.

More particularly, the goggles may, for instance, consist of a frame 14 (see Fig. 1) having a substantially horizontally disposed bridge portion 15 which may be formed integrally with the temple portions 16, also having an integral frontal portion 17 which serves to support lens-mounts 8 which may be of the usual construction, or more particularly of the ventilated type more fully described and claimed in my copending application filed concurrently herewith.

The bridge portion 15 is divided into two sections, 18 and 19 respectively, by a cut or slot 20 which extends to the point 21 which is substantially at the line of junction of the bridge portion 15 with the frontal portion 17. By reason of the flexibility of the frontal portion 17, the two sections 18 and 19 can be made to approach or recede from each other in a sort of pivotal movement which has its approximate center at the point 21. Therefore the contour of the brow-contacting edge 22 can be varied between two extremes, in other words, from a point where the sections 18 and 19 are substantially touching each other closing the slot 20, up to a point where they are shown in the separated position best seen in Figs. 3 and 4.

In order to enable the user to set or lock the goggles in a position of final adjustment there is provided the locking member 23, which may take the form of a suitable plate made either of metal or other suitable material, and which bridges the slot 20. Cooperating with said plate are bolts 24 which pass through slots 25 and 26 provided respectively in the two sections 18 and 19 of the bridge member 15 and holes 27 provided in the plate. The slots 25 and 26 are elongated and in arcuate arrangement relative to the pivotal point 21 in order to allow for relative movement of said bridge sections. This construction is best seen in Figs. 3, 6 and 9. Knurled nuts 28 engage the bolts 24 whereby the locking member 23 may be tightly forced against the two sections 18 and 19 of the bridge member 15, thereby locking said sections in any position of adjustment. In order further to hold the bolts 24 against rotation suitable lock washers 29 may be provided.

If desired, the bridge member 15 and the temple members 16 may be provided with one or more ventilating openings 30 and 31. These ventilating openings may be covered by a fine screen to prevent passage of particles of material. In order to hold the goggles against the face of the wearer they may be provided with an adjustable strap 32 the ends of which are passed through apertures 33 at each side of the temple pieces 16. In the embodiment shown in Figs. 1 through 6 are also shown suitable lenses 34 which are mounted in lens-retaining rings 35.

The goggles illustrated in Figs. 1 through 6 are used in the following manner: With the knurled nuts 28 loosened so as to permit free relative movement of the sections 18 and 19 of the bridge member 15, the goggles are applied to the face of

the wearer and the strap adjusted to a comfortable position and secured. This will allow the sections 18 and 19 to be adjusted into snug engagement with the wearer's brow, whereafter the knurled nuts 28 are screwed down tightly so as to lock the parts in their positions of adjustment. The goggles having thus been adjusted and made fast, can be taken off and laid aside with the assurance that when they are again applied to the same head they will accurately fit. This adjustability is of particular advantage when the goggles are used, for example, by grinders, welders or chippers, as it will insure a sufficiently tight fit between the brow-contacting portions and the wearer's brow so as to prevent particles from entering the interior of the goggles.

The goggles illustrated in Figs. 1 through 6 may be made of either an opaque or transparent material which may be either a suitable plastic such as cellulose ester or ether, cellulose acetate, cellulose acetobutyrate, ethyl cellulose, or a transparent plastic material such as a methyl methacrylate resin. If desired, however, the parts may be made of vulcanized fiber or metal.

A goggles frame embodying the essential features of the present invention but made entirely from vulcanized fiber, is illustrated in Figs. 7 through 11. In this form the bridge member 45 is divided into two relatively movable sections 48 and 49 by the slot 50. In order that the sharp edges of the vulcanized fiber may not bear against the skin of the wearer, a brow-contacting soft rubber cushion strip 52, U-shape in cross section, is provided, this being sufficiently elastic so that it will either stretch or contract with the relative movement of the sections 48 and 49 of the bridge member. This cushion strip is secured as by stitching to the edge portion of bridge member 45. The slot 50 terminates substantially at the point 51 which is located on the line of junction of the bridge member 45 with the frontal member 47. A slot-bridging member 53 is provided, which in this case may be also made of vulcanized fiber, one dependent corner of which 54 is secured to the frontal member 47 by means of the rivet 55. The means for securing the portions 48 and 49 in their positions of relative adjustment are the same as described in connection with Fig. 1, and hence do not require further explanation. A suitable strap 56 is provided to hold the goggles to the face of the wearer.

The method of ventilating this particular type of goggles comprises openings 57 which are provided in each of the temple pieces 46, and are surmounted by rearwardly extending hoods 58 which prevent any particles flying in the direction of the wearer from passing through the openings 57. The hoods 58 are preferably riveted to the temple portions 46 by means of rivets 59, 60 and 61.

The structure of the lens-holding mechanism is the same as of goggles illustrated in Figs. 1 through 6, and hence does not require further explanation.

A third modification of the goggles is illustrated in Figs. 12 and 13, the goggles in this case comprising a single piece of material having a substantially horizontal bridge portion 65, and temple portions 66, the frontal portion, however, consisting merely of a frame 67 and a central portion 67' which lies immediately above the nose, thus providing two eye openings, 62 and 63 respectively. Subtending the said eye-openings and also the temple portion 67' of the

frontal member 67 is a transparent sheet 68 of plastic material, such for example as cellulose acetate or methyl methacrylate resin, the edges of which at the top and bottom, respectively, are slightly rearwardly crimped or bent so as to contact, respectively, at 69 the bridge member 65, and at 70 the lower portion of the frontal member 67. The lateral edges 71 and 72 of the lens member 68 are, however, of reduced thickness so that a small space may exist between the temple member 66 and the lens member 68 to allow for a certain amount of ventilation. Moreover, and for purposes of affixing the lens member 68, there are provided a plurality, for example four, of S-clips 73, the rearward portions thereof engaging the inwardly bent edges 74 (Fig. 13) of the temple member 66, while the front portion 75 is bent against the outer face of the lens member 68 (see Fig. 13). The bridge member 65 is divided into two sections 78 and 79 by means of the slot 80 which terminates at about the point 81 at the point of juncture of the bridge member with the frontal member.

A locking member 83, entirely similar in construction and function to that employed in the form shown in Figs. 1 to 6, is also provided, there also being the locking screws and cooperating knurled nuts 28. However, the locking member 83 in this case performs a second function, involving the downwardly turned lip 84 which overlies the lens member 68 and serves the purpose of holding it in place, this being particularly necessary when the bridge and frontal members are flexed, as otherwise a gap would be formed between the upper edge of the lens member and the side of the bridge member. Moreover, by completely unscrewing and removing the nuts 28, the locking member or plate 83 may be removed and the lens then slid out of engagement with the retaining S-clips 73, for repair or replacement of the lens, or said nuts may be simply unscrewed sufficiently to allow the plate 83 to rock upwardly to such an extent as to allow the lens to slip by the lip 84 of said plate.

All of the goggles illustrated hereinabove described have the common feature of the adjustable bridge portion which is divided into at least two relatively movable sections by a cut extending across said bridge member and terminating substantially at the frontal member. It will be self-evident that more than one slot 20, 50 or 80 may be employed, in which case the bridge member will be divided into more than two relatively movable sections. The locking member illustrated and hereinabove described may of course subtend a plurality of such slots or slits, it being only necessary that at least two of the sections may be rigidly connected with each other and locked in a position of adjustment by means of a locking member 23, 53 or 83.

All of the goggles disclosed herein are characterized by having integrally formed bridge, temple and frontal members, the latter either serving directly as a lens or at least carrying lenses and/or lens-mounts thereon. The temple and bridge members may be either transparent, translucent, or opaque, and the lens portions may be tinted or colored, as may be desirable, depending upon the intended use of the goggles.

Saving for himself such equivalents as will occur to those skilled in the art into which the present invention falls, applicant claims:

1. Goggles made of substantially rigid self-supporting but somewhat flexible material com-

prising substantially vertically disposed temple and unitary flexible frontal portions, the latter having eye openings therein, and a substantially horizontally disposed brow-contacting bridge portion integrally connected with said temple and frontal portions, said bridge portion being subdivided into at least two sections by a transverse horizontal slot terminating at said frontal portion thereby permitting relative movement between the resulting sections of the bridge portion and also permitting a flexing movement of the frontal portion; a flexible transparent eye shielding lens member mounted on said frontal portion and subtending said eye openings, and a removable plate bridging said slot and adjustably secured, respectively, to at least two sections of said bridge portion and also provided with a projection overlying the upper edge of said lens-member to aid in maintaining it in place.

2. Goggles made of substantially rigid self-supporting but somewhat flexible material comprising substantially vertically disposed temple and unitary flexible frontal portions, the latter having eye openings therein, and a substantially horizontally disposed brow-contacting bridge portion integrally connected with said temple and frontal portions, said bridge portion being subdivided into at least two sections by a transverse horizontal slot terminating at said frontal portion, thereby permitting relative movement between the resulting sections of the bridge portion and also permitting a flexing movement of the frontal portion; a flexible transparent eye shielding lens-member mounted on said frontal portion and subtending said eye openings, a removable plate bridging said slot and adjustably secured, respectively, to at least two sections of said bridge portion, and also provided with a projection overlying the upper edge of said lens-member to aid in maintaining it in place, and clips attached to said temples having ears engaging the lateral edges of said lens-member.

3. Goggles made of substantially rigid self-supporting but somewhat flexible material comprising a substantially vertically disposed temple and a similarly disposed unitary flexible frontal portion, the latter provided with eye openings, a substantially horizontally disposed brow-contacting bridge portion connected with said temple and frontal portions, and a single lens-member mounted on said frontal portion and subtending said eye openings, the upper and lower edges of said lens-member being crimped respectively against the bridge portion and the frontal portion to prevent projected particles from penetrating between said portions and said lens-member.

4. Goggles made of substantially rigid self-supporting but somewhat flexible material comprising a substantially vertically disposed temple and a similarly disposed unitary flexible frontal portion, the latter provided with eye openings, a substantially horizontally disposed brow-contacting bridge portion connected with said temple and frontal portions, and a single lens-member mounted on said frontal portion and subtending said eye openings, the upper and lower edges of said lens-member being crimped respectively against the bridge portion and the frontal portion to prevent projected particles from penetrating between said portions and said lens-member, said lens-member being cut away and reduced in thickness along the lateral edges adjacent the temple portions and spaced therefrom to

7 permit ventilation, and clips attached to said temples having ears engaging said lateral edges.

5. Goggles made of substantially rigid self-supporting but somewhat flexible material comprising a substantially vertically disposed temple and a similarly disposed unitary flexible frontal portion, the latter provided with eye openings, a substantially horizontally disposed brow-contacting bridge portion connected with said temple and frontal portions, and single lens member mounted on said frontal portion and subtending said eye openings, the upper and lower edge of said lens member being crimped respectively against the bridge portion and the frontal portion to prevent projected particles from penetrating between said portions and said lens member, said lens member being cut away and reduced in thickness along its lateral edges adjacent the temple portions and spaced therefrom to permit ventilation, clips attached to said temples having ears engaging said lateral edges, and a locking member secured to said bridge portion having a projection extending over the upper edge of said lens member.

6. In goggles made of substantially rigid self-supporting but somewhat flexible material having integrally connected unitary flexible frontal lens-supporting and substantially horizontally disposed brow-contacting bridge members, the improvement which comprises providing the bridge member with a transverse slot terminating at the juncture with the lens-supporting member permitting movement of the thus formed sections thereof and a corresponding flexing movement of said frontal member.

7. In goggles made of substantially rigid self-supporting but somewhat flexible material having an integrally connected unitary flexible frontal lens-supporting member and a substantially horizontally disposed brow-contacting bridge member, the improvement which comprises providing the bridge member with a transverse slot terminating at the juncture with the lens-supporting member permitting movement of the thus formed sections thereof and a corresponding flexing movement of said frontal member, and means for securing said sections of said bridge member together comprising a plate bridging said slot and bolts and cooperating nuts for securing said plate to said sections.

8. In goggles made of substantially rigid self-supporting but somewhat flexible material having integrally connected unitary flexible frontal lens-supporting and brow-contacting bridge members, the improvement which comprises providing the bridge member with a transverse slot terminating at the juncture with the lens-supporting member permitting movement of the thus formed sections thereof and a corresponding flexing movement of said frontal member, said bridge member being provided with holes, a locking plate having holes registering with the holes in said bridge member, bolts passing

through said holes in said bridge member and plate, and nuts engaging said bolts for securing said plate to said bridge member.

9. Goggles adjustable to the contour of the wearer's face and constructed of a substantially rigid self-supporting but somewhat flexible material comprising a substantially vertically disposed one-piece lens-carrying portion, a thereto attached substantially horizontally disposed brow-contacting bridge portion which latter is divided into a plurality of sections movable relative to each other by a horizontally extending slot terminating at the lens-carrying portion.

10. Goggles adjustable to the contour of the wearer's face and constructed of a substantially rigid self-supporting but somewhat flexible material comprising a substantially vertically disposed one-piece lens-carrying portion, a thereto attached substantially horizontally disposed brow-contacting bridge portion which latter is divided into a plurality of sections movable relative to each other by a horizontally extending slot terminating at the lens-carrying portion, and a locking member positioned above and across said slot and securable to at least two of said sections to lock the same in position for relative adjustment.

11. In goggles that are adjustable to the contour of the wearer's face and which are constructed of substantially rigid self-supporting but somewhat flexible material, and which have a one-piece lens-carrying substantially vertical portion and a horizontal brow-contacting bridge portion integral with said lens-carrying portion, the improvement which comprises the provision of a horizontal slot in said bridge portion terminating at its juncture with the lens-carrying portion thereby dividing said bridge portion into two sections adjustable relative to each other, and a locking member subtending said slot and adjustably secured to said sections to permit holding said sections in a selected mutual relationship.
